UNITED STATES PATENT OFFICE

114,628

DESIGN FOR AN ELECTRICAL INSTRUMENT CASING

Albert G. Babo, South Pasadena, Calif., assignor
to The Birtcher Corporation, Los Angeles, Calif.,
a corporation of California

Application February 13, 1939, Serial No. 82,943

Term of patent 7 years

To all whom it may concern:

Be it known that I, Albert G. Babo, a citizen of the United States, residing at South Pasadena, in the county of Los Angeles, State of California, have invented a new, original, and ornamental Design for an Electrical Instrument Casing, of which the following is a specification, reference being had to the accompanying drawing, forming a part thereof,

Fig. 1 is a perspective view of the electrical instrument casing, showing my new design;

Fig. 2 is a plan view thereof;

Fig. 3 is an end elevation thereof; and

Fig. 4 is a side elevation thereof.

I claim:

The ornamental design for an electrical instrument casing, as shown.

ALBERT G. BABO.
